UNITED STATES PATENT OFFICE.

RUDOLF WAGNER, OF HAMBURG, GERMANY.

COUNTER PROPELLER FOR AIR PROPELLER-DRIVEN CRAFT.

Application filed October 10, 1925, Serial No. 61,724, and in Germany March 14, 1925.

This invention relates to counter propellers and more particularly to counter propellers mounted on air propeller driven crafts.

The counter propeller is in general a fixed propeller mounted behind the main or rotating propeller considered in the direction of motion. The main propeller causes the fluid in which it operates to leave it in a rotary or swirling movement, and the function of the counter propeller is to receive the rotary fluid currents and change their direction into an axial flow, and thus increase the effectiveness of the drive of the craft by imparting a forward thrust obtained from changing the rotary fluid currents into axially directed currents.

In mounting a fixed counter propeller behind a main propeller in crafts driven by air propellers, and particularly, in aircraft having motor drive, there are certain difficulties as compared with those of watercraft. In the aircraft there is generally no structural part, such for example, as the rudder posts in watercraft, to which can be attached the counter propeller. Furthermore, in the air propelled craft the main propeller is relatively much larger than is the case in watercraft.

In any arrangement of the counter propeller independently of the shaft of the main propeller it is generally necessary to have relatively long arms connecting the counter propeller to the body of the craft, which arms offer additional air resistance.

This invention overcomes this difficulty mentioned above by mounting the counter propeller directly on a prolongation of the main propeller shaft so that the useful thrust of the counter propeller is transmitted to the main propeller shaft. The rotary moment acting on the counter propeller is taken up by a connection from the counter propeller to the body of the craft and this connection is arranged so as to form no obstacle to the adjustment of the main propeller shaft. It is entirely feasible to mount the counter propeller directly on the main propeller shaft since this weight is slight and since it exerts no centrifugal or like forces.

For transmitting the rotary moment of the counter propeller to the craft body, in the present construction only relatively thin tension or thrust elements are necessary, and such elements offer no appreciable air resistance.

For taking up the rotary moment of the counter propeller there can also be used a prolongation of one of the blades of the counter propeller which engages in a grooved holding lug mounted on the craft body.

In the accompanying drawings merely by way of example, are shown three forms of construction in accordance with this invention.

In the drawings:

Fig. 1 is a rear end elevation of the counter propeller arrangement connected to a motor driven lighter than aircraft.

Fig. 2 is a side elevation of the construction shown in Fig. 1.

Fig. 3 is a view similar to that of Fig. 1, of a slightly modified form of construction.

Fig. 4 is a top plan view of a further form of construction as applied to a motor for heavier than air craft.

Fig. 5 is a rear end elevation of the construction shown in Fig. 4.

Referring to Figures 1 and 2 an airship body is shown at 1 with a gondola 2 to which is fitted a main air propeller 3 which rotates in the direction of the arrow of Fig. 1, for forward travel. A four-bladed counter propeller 4 is journaled by means of ball bearings 5 on a prolongation of the main propeller shaft 5' so as to afford an axle guide for the counter propeller.

The turning moment acting on the counter propeller due to the action therewith of the rotary off-flow from the main propeller is transmitted through a loosely pivoted tension member 6, to the craft body 1, the member 6 being loosely mounted to permit free adjustment of the propeller shaft 5'.

In the construction as described the turning moment of the counter propeller tends to raise the counter propeller about the point 7, the connection between the member 6 and the counter propeller, so that there arises an upward force on the main propeller shaft bearing 9, in the direction of arrow 8 of Fig. 1. This upward force partly counterbalances the weight of the main and counter propeller so that the use of the counter propeller as described above, results in more favorable conditions for the main propeller bearings than would otherwise exist.

While the member 6 is preferably designed to take both tension and compression so as to function properly, on reverse rota-

- tion of the main propeller 3, if desired, a construction as shown in Figure 3 can be used wherein the member 6' is designed for tension only and a second member 10 designed for tension only is connected between the counter propeller and the craft body for taking up the turning moment of the counter propeller on reversal of the direction of rotation of the main propeller.
- 10 Referring to Figures 4 and 5 wherein the counter propeller arrangement is shown in connection with a motor driven heavier than aircraft, the craft is shown at 11 having wings 12 and a drive motor 13. The main propeller 14 is mounted on a shaft having an extended portion in the same manner as in connection with Figures 1 and 2. In this form of construction the counter propeller 15 which is mounted on the main propeller shaft has an extension 16 on one of its blades and this extension loosely engages in a U-shaped holding lug 17 which is fixed to the body 11 of the craft. This connection between the parts 16 and 17 prevents rotation of the counter propeller due to its turning moment received from the rotating currents of fluid leaving the main propeller blades. In this construction the counter propeller is held from rotation in both directions and, hence, is adapted for use with the main propeller rotating either forward or backward.
- 25 The U-shaped holding member 17 readily permits all necessary adjustment of the main propeller shaft.
- 30 As in the cases above the direction of rotation of the main propeller for forward movement is so selected that an upwardly acting reaction is obtained as indicated by the arrow 18 of Figure 5, and such reaction relieves the propeller shaft bearings of part of the weight of the propellers.
- 35 In addition to the above examples of construction in accordance with this invention the inventive idea can of course be carried out in many other manners and furthermore, can of course be used for other than air propeller driven craft. The invention can be readily used for land and water-craft without exceeding the scope of the inventive idea.

Having now described my invention, I claim:—

- 40 1. A counter propeller device for craft which are driven by a main propeller on a propeller shaft, comprising a counter propeller journaled on the main propeller shaft in the path of the rotary air outflow from the main propeller, and a connection between the counter propeller and the craft body for taking up the turning moment of the counter propeller, the connection being constructed to permit adjustment movements 45 of the main propeller shaft.
- 45 2. A counter propeller device for craft which are driven by a main air propeller on a propeller shaft, comprising a counter propeller journaled on the main propeller shaft in the path of the rotary air outflow from the main propeller, and a connection between the counter propeller and the craft body for taking up the turning moment of the counter propeller, the connection acting at the end of a counter propeller blade and being constructed to permit adjustment movements 50 of the main propeller shaft.
- 50 3. A counter propeller for craft driven by air propeller means, comprising, a craft having a body, a main propeller, a shaft carrying the main propeller, a counter propeller journaled on an extended portion of the main propeller shaft and a connection between the counter propeller and the craft body for taking up the turning moment of the counter propeller, the connection comprising, an extension on one of the counter propeller blades and a holding lug on the craft body loosely engaging the extension whereby to permit ready adjustment of the main propeller shaft.
- 55 4. A counter propeller device for craft which are driven by a main air propeller on a propeller shaft, comprising a counter propeller journaled on the main propeller shaft in the path of the rotary air outflow from the main propeller, and a connection between the end of a counter propeller blade and the craft body for taking up the turning moment of the counter propeller, said connection being constructed to permit adjustment movements of the main propeller shaft, and connected to the counter propeller on the descending side of the arc of rotation thereof whereby an upwardly directed force is caused by the reaction therewith of the turning moment of the counter propeller.

- 60 5. A counter propeller for craft driven by air propeller means, comprising, a craft having a body, a main propeller, a shaft carrying the main propeller, a counter propeller journaled on an extended portion of the main propeller shaft and a connection between the counter propeller and the craft body for taking up the turning moment of the counter propeller, the connection being arranged to permit adjustment of the main propeller shaft, and comprising, an extension on one of the counter propeller blades, and a holding lug on the craft body loosely engaging the extension, the connection being so arranged that, on forward movement of the main propeller, an upwardly directed force is caused by the reaction therewith of the turning moment of the counter propeller.

65 In testimony whereof I have signed my name to this specification.

RUDOLF WAGNER.
